THEODORE F. POPE, OF HOMINY, OKLAHOMA

MANHOLE COVER

Application filed May 21, 1930. Serial No. 454,406.

This invention appertains to storage tanks for oil and other liquids and more particularly to a novel cover or plate for the manhole thereof.

5 One of the primary objects of my invention is to provide a novel form of manhole cover or plate and novel means for holding the cover or plate on its seat, so as to preclude leakage around the plate and to provide 10 novel means for raising the cover or plate off of its seat, when it is desired to gain access into the tank.

Another salient object of my invention is the provision of a single shaft or bolt holding 15 the cover or plate on its seat and for lifting the cover off of its seat and holding the same in a raised position above the seat to permit access to be readily had into the tank.

A further important object of my invention 20 is the provision of an adjusting shaft having swivelly connected therewith a manhole cover or plate, the adjusting shaft being threaded and adjustably associated with an interior bracket rigidly secured to the 25 tank, whereby upon turning movement of the shaft the manhole cover or plate can be carried into intimate contact with the seat or raised and held away from its seat.

A still further object of my invention is to 30 provide an improved manhole cover or plate for oil storage tanks, of the above character, which will be durable and efficient in use, one that will be simple and easy to manufacture, and one which can be placed upon the market 35 at a reasonable cost.

With these and other objects in view, the invention consists in the novel construction, arrangement and formation of parts, as will be hereinafter more specifically described, 40 claimed, and illustrated in the accompanying drawing, in which drawing:

Figure 1 is a transverse section through a storage tank equipped with my improved manhole plate or cover.

45 Figure 2 is a section taken on the line 2—2 of Figure 1 looking in the direction of the arrows, illustrating the construction of the manhole cover or plate.

Figure 3 is a detail section taken on the 50 line 3—3 of Figure 2 looking in the direction

of the arrows, showing the inner end of the manhole cover or plate.

Referring to the drawing in detail, wherein similar reference characters designate corresponding parts throughout the several views, the numeral 10 indicates an oil or other storage tank which may be of conventional character. The storage tank 10 is provided with the manhole 11 which, in accordance with my invention, is surrounded 55 by an outstanding flange 12. This flange 12 flares outwardly and gradually increases in diameter thereof toward its outer end forming a tapered seat for the manhole cover or plate 13.

60 The manhole cover or plate 13 comprises a cylindrical body having the inner ends thereof tapered or beveled as at 14 so as to fit within the tapered seat provided by the flange 12 and to make an intimate contact 65 therewith. This cover or plate 13 is provided with an axial bore 15 the outer end of which is enlarged to provide a pocket or seat 16, for a purpose which will be later described.

70 Slidably extending through the bore 15 of the cover or plate 13 is the shaft 17, having formed thereon intermediate its ends the shoulder or annular collar 18, the opposite 75 ends of which are rounded to form a substantial ball for fitting against the inner end of the seat or pocket 16 of the plate or cover 13 which limits outward movement of said cover or plate on the shaft. The outer face 80 of the cover or plate 13 is provided with an externally threaded axially disposed sleeve 19 which surrounds said shaft and this sleeve has threaded thereon the cap 20 which is also loosely mounted on the shaft. The cap 20 confines a split sleeve 22 which is likewise 85 mounted on the shaft and the inner end of the sleeve engages the outer face of the collar or annular enlargement 18 formed on the shaft. Thus the cap or cover is prevented 90 from having endwise movement of the shaft but is permitted of slight rocking motion so as to insure the proper seating of the cover or plate on its seat 12. The inner end of the shaft 17 is threaded and is received within 95 the bore 23 of a bracket 24 rigidly secured

100

to the inner face of the tank 10, the bore 23 being in axial alignment with the manhole 11.

The outer end of the shaft is provided with a suitable crank or manipulating handle 25.

It is obvious from the foregoing description that upon turning movement of the shaft 17 in one direction that the shaft will be threaded in the bracket 24, consequently bringing the cover 13 into contact with the seat 12 and due to the association of the cover with the shaft a perfect seat between the cover and flange is permitted.

When the shaft is rotated in the opposite direction the same will move outward of the bracket carrying the cover or plate 13 therewith moving the same away from its seat and holding the same in any desired position off of the seat.

From the foregoing description, it can be seen that I have provided a novel manhole cover or plate and novel means for moving the cover off and on its seat.

Changes in details may be made without departing from the spirit or the scope of this invention, but:-

What I claim as new is:

1. The combination with a storage tank having a manhole therein, and an annular flange surrounding the manhole tapered outwardly to provide a seat, of a bracket secured to the inner face of the tank having a threaded bore in axial alignment with the manhole, a shaft extending through the manhole and threaded into said bore, a cover movable with the shaft toward and away from the seat, and means for rotating the shaft.

2. The combination with a storage tank having a manhole and a flange surrounding the manhole flared outwardly to provide a tapered internal seat, of a manhole cover having an axial bore and having its inner end beveled for engaging the tapered seat, a bracket secured to the interior of the tank having a threaded bore in axial alignment with the opening, a shaft extending through the bore of the cover and threaded into the bore of the bracket, the bore of the cover being enlarged adjacent to its outer end to provide a seat, an enlargement of the shaft for engaging the last mentioned seat, an extension on the cover, a cap fitted on the extension, a resilient sleeve on the shaft confined between the cap and the shoulder, and means for rotating the shaft.

In testimony whereof I affix my signature.
THEODORE F. POPE.
